GEORGE W. HULSHIZER, OF STEWARTSVILLE, NEW JERSEY, ASSIGNOR TO INGERSOLL-RAND COMPANY, OF JERSEY CITY, NEW JERSEY, A CORPORATION OF NEW JERSEY

ANCHOR FOR DRILLING MECHANISM

Application filed February 19, 1929. Serial No. 341,193.

This invention relates to rock drills, but more particularly to an anchor for rock drills of the stoper type having rotation mechanism for constantly changing the position 5 of the working implement preparatory to the delivery of the blows of the hammer piston.

The rock drill may be provided with a suitable handle against which manual pressure may be applied to resist the tendency of the 10 drill to follow the movement of the rotation mechanism. Normally, under favorable conditions, a slight pressure may suffice to hold the drill against rotary movement. Under other conditions, however, and particularly 15 where soft strata are encountered by the drill steel, the drill steel advances very rapidly, so that instead of forming a drill hole of generally cylindrical shape, the wings of the drill bit will rifle the material being drilled.

20 When employing drills equipped with automatic rotation mechanism all of the elements through which rotation is transmitted to and including the drill steel are of course interlocked with each other and, since the thrust 25 for rotating these elements reacts against the stationary elements of the drill, it will readily be seen that when the hole becomes rifled the entire drilling mechanism tends to rotate with the drill steel. When this occurs a heavy 30 thrust is imparted to the portion against which the operator applies pressure, such as the handle, and it happens not infrequently that the handle is jarred out of the operator's grasp. The drill is then of course free to rotate about its axis and unless the operator has 35 sufficient room to quickly remove himself from the range of the rapidly rotating handle, he may suffer serious injury.

The present invention contemplates the 40 elimination of chances of injury to the operator by so anchoring or securing the drilling mechanism that irrespective of what may take place in the drill hole the drilling mechanism will not rotate about its axis unless by 45 the will of the operator.

Another object is to enable the anchoring means to be readily rocked out of the anchoring 50 position into a released position and to be retained in the latter position in a simplified manner until conditions in the drill hole are

again such that the anchor may be placed in engagement with an abutment for preventing rotary movement of the drill.

Other objects will be in part obvious and in part pointed out hereinafter.

In the drawings illustrating the invention and in which similar reference characters refer to similar parts,

Figure 1 is a elevation partly in section 60 of a stoper type rock drill having the invention applied thereto,

Figure 2 is a sectional enlarged elevation 65 illustrating in detail the manner in which the anchor is secured to the feed rod and showing the anchor in engagement with an abutment,

Figure 3 is a view taken through Figure 2 on the line 3—3 looking in the direction indicated by the arrows,

Figure 4 is a view similar to Figure 2 showing the anchor in the released position,

Figure 5 is an elevation partly in section 70 of a modification of the invention, and

Figure 6 is a transverse view taken through Figure 5 on the line 6—6 looking in the direction indicated by the arrows.

Referring to the drawings, A designates generally a rock drill of the stoper type comprising a percussive element B and a feeding element C. The percussive element shown in outline comprises a cylinder D to the front end of which is secured a front head E and to the rearward end a head block F. A drill steel G extends into the front head E wherein it is guided and interlocked with a chuck H, only a portion of which is shown protruding from the end of the front head E.

The rock drill illustrated is intended to represent one of the type in which automatic rotation mechanism is provided for imparting rotary movement to the drill steel G. The rotation mechanism is not shown, but it is to be understood that it may be of any suitable type capable of imparting a step by step rotary movement to the drill steel preparatory to the delivery of the blows of the hammer piston (not shown).

The admission of pressure fluid to the drill may be controlled by a throttle valve (not shown) but the position of which is indicat-

ed by a lever J adjacent the head block F. Secured to the head block F is a handle K which may be grasped by the operator for manually rotating the drilling mechanism.

The feeding mechanism C comprises the usual cylinder L which may be secured to the head block F by any suitable means, such as bolts O, which as illustrated, may also clamp the feeding cylinder L and the percussive cylinder D together.

- 10 Within the feeding cylinder L is disposed a feeding piston P carrying a feed rod Q illustrated in this instance as being of rectangular cross section. The rod Q extends through a rectangular aperture R in a head S forming a closure for the lowermost end of the feed cylinder L. In the projecting or lowermost end of the feed rod Q is a pointer T adapted to engage an abutment, such as a mine floor, or as illustrated, a plank U which may be disposed on the mine floor and which the pointer T may penetrate to prevent the drilling mechanism from moving out of the operative position.

From the foregoing it will readily be observed that there cannot be any relative rotation between the feeding element and the casting parts of the percussive element. In other words, even though the resistance to the rotation handle K were removed to permit the drilling mechanism to rotate with the drill steel the feed rod would also rotate with the feeding cylinder.

In accordance with the present invention additional means, other than the handle K, are provided for insuring against unauthorized rotation of the drilling mechanism. To this end the feed rod Q is provided near its lowermost end with a transverse slot V which opens in this instance in opposite sides of the feed rod, thus leaving walls W and X on opposite sides of the slot V. Apertures Y and Z are formed in the walls W and X respectively for the reception of a pivot pin b which extends through the slot V and in this instance has a threaded end c carrying a nut d for drawing the pivot pin b firmly into the apertures Y and Z.

The pivot pin b in most respects resembles a bolt and has flat opposed surfaces e and f which preferably extend along the entire unthreaded portion of the pivot pin. On one end of the pivot pin b are inclined portions g to engage correspondingly inclined notches h adjacent to and merging into the aperture Y and having flat sides as has also the aperture Y to engage the flat surfaces e and f of the pin b for preventing rotation of the pivot pin relatively to the rod Q. The notches h are inclined with respect to the longitudinal axis of the feed rod Q so that the flat surfaces e and f will therefore also assume an inclined position with respect to the axis of the feed rod.

65 The pivot pin b serves as a pivot for an

anchor j in the form of a hook having a pointer k adapted to be driven into the plank U. The opposite end of the anchor extends into the slot V and is provided with an aperture o for the reception of the pivot pin b. 70 The aperture o is shown as being of cylindrical form and a slot p is formed in the anchor j adjacent the aperture o into which it opens at one side. Preferably the slot p is only of slightly greater width than the spacing of the 75 flat surfaces e and f of the pivot pin b.

In the form of the anchor j illustrated, said anchor has converging portions q and r, the aperture o and the slot p being formed in the portion q. At the outer end of the portion r 80 is a downwardly projecting portion or hook s which carries the pointed end k. The portion r is preferably so arranged with respect to the portions q and s that when the anchor j is in substantially the operative 85 position, said portion r will assume a position approaching the horizontal and it is against this portion that hammer blows may be struck for driving the end k into the plank U.

In practice, when drilling rock of substantially uniform hardness, the anchor j will occupy the position shown in Figures 1 and 2, that is, the pointed end k will be in engagement with the abutment, such as the plank U. When the anchor is thus positioned the 90 rock drill will be adequately held against any form of rotary movement and it will be unnecessary for the operator to hold it against rotation. He may therefore give his entire 95 attention to the controlling devices, such as drills of this type are provided with for controlling the percussive and feeding elements.

When the drill steel tends to stick in the drill hole the pressure fluid supply to the percussive element may be cut off and the anchor may be rocked to the position illustrated in Figure 4 and moved endwise so that the slot p will engage the flat surfaces e and f of the pivot pin. In this way the anchor j will be retained in the released position. 110

With the anchor j in the released position, the operator may then grasp the handle K and after the percussive element is again set in operation may oscillate the entire drilling mechanism by hand, thus assuring a cylindrical hole in the soft material. After the drill steel G again encounters material in which the rotation mechanism will suffice to assure a cylindrical hole, the anchor j 115 may again be driven into the plank U and normal drilling may then be resumed.

In the modification illustrated in Figures 5 and 6 a pair of members t and u are disposed on opposite sides of the feed rod Q and are clamped together by pivot pins b extending through lugs v and w on opposite ends of the members t and u respectively. The lugs v and w are so spaced with respect to each other as to form slots x therebetween for the 120 reception of anchors j, two being shown in 125

this modification. Preferably the feed rod *Q* is slightly reduced as at *y* to form shoulders *z* which will engage the sides of the members *t* and *u* to assure the correct position of said members on the feed rod. The pivot pin *b* and the anchors *j* may be in all respects like those shown in the preferred modification so that whenever it is desired to rotate the rock drill by hand the anchors *j* 10 may be readily moved into and held in the released position by the pivot pins *b*.

I claim:

1. In a rock drill, the combination of a percussive element and a feeding element, said 15 feeding element comprising a cylinder and a piston, a polygonal bore in the cylinder, a rod on the piston slidable in the bore and in engagement therewith to prevent rotation of the piston with respect to the cylinder, a slot 20 in the feed rod, a pivot affixed to the feed rod and extending transversely through the feed rod and the slot and having a flat surface, and an anchor rotatable about the pivot and adapted to engage an abutment for preventing rotation of the rock drill, said anchor being adapted to interlock with the pivot for holding the anchor in the released position.

2. In a rock drill, the combination of a 30 percussive element and a feeding element, said feeding element comprising a cylinder and a piston, a polygonal bore in the cylinder, a rod on the piston slidable in the bore and in engagement therewith to prevent rotation of the 35 piston with respect to the cylinder, a slot in the feed rod, a fixed pivot extending transversely through the feed rod and the slot and having opposed flat surfaces, an anchor having an aperture through which the pivot 40 extends and to enable said anchor to be oscillated about the pivot, said anchor having a pointer for engagement with an abutment for preventing rotation of the rock drill, and a slot merging into the aperture to engage 45 the flat surfaces for retaining the anchor in a released position.

In testimony whereof I have signed this specification.

GEORGE W. HULSHIZER.
